UNITED STATES PATENT OFFICE

EDWIN S. MIX, OF ROCHESTER, NEW YORK, ASSIGNOR TO HICKOK MANUFACTURING COMPANY, INC., OF ROCHESTER, NEW YORK, A CORPORATION OF NEW YORK

FLEXIBLE BUCKLE BELT

Application filed November 30, 1931. Serial No. 578,151.

The object of the invention is to embody a flexible buckle construction in combination with the belt.

Another object of the present invention is to improve the construction of flexible buckle belts and to provide a belt equipped with a buckle of the two loops and tongue type in which the body portion of the buckle or portion connecting the loops and the tongue will be formed by a portion of the belt whereby a flexible buckle is provided to afford flexibility of manipulation, that is, entrance of the buckle engaged end of the belt into the buckle and its removal therefrom and at the same time increase the comfort of the belt in permitting it to conform to the contour of the body of the wearer and lie flat against the same.

It is also an object of the invention to provide a belt and buckle of this character of not only economical construction as a whole but also adapted to materially lessen the cost of manufacture by reducing the amount of metal or other material required for the buckle as compared with similar and other types of complete buckles.

Another object of the invention is to provide a flexible buckle belt comprising two loops and a tongue which will be characterized by great simplicity of manufacture and also by economy and rapidity of assembly.

With these and other objects in view, the invention consists in the construction and novel combination and arrangement of parts hereinafter described, illustrated in the accompanying drawing, and set forth in the claims hereto appended, it being understood that various changes in the form, proportion, and minor details of construction, within the scope of the claims, may be resorted to without departing from the spirit of the invention or sacrificing any of the advantages thereof.

45 In the drawing:—

Figure 1 is a front elevation of a portion of a belt provided with a flexible buckle constructed in accordance with this invention.

Fig. 2 is a similar view of the buckle end 50 of the belt.

Fg. 3 is an enlarged longitudinal sectional view on the line 3—3 of Fig. 2.

Fig. 4 is a transverse sectional view on the line 4—4 of Fig. 2.

Fig. 5 is an elevation of the buckle end of 55 a strap illustrating a modification of the invention and viewed from the inner face of the strap, a portion of the patch being broken away to show the tongue and pivot.

Fig. 6 is an enlarged longitudinal sectional 60 view of the same.

In the accompanying drawing in which is illustrated the preferred forms of the invention the flexible buckle belt comprises in its construction a belt 1 of leather or other 65 suitable material which has the buckle end portion split longitudinally, as indicated at 2, to permit the assembly of inner and outer spaced loops 3 and 4 and an intermediate tongue 5 which is mounted on a suitable pivot 70 6 and which is adapted to engage holes 7 in the other end portion of the belt. The loops which may be constructed of metal or any other suitable material and which may be embossed, engraved, colored or otherwise 75 ornamented to harmonize with and ornament the belt 1 are preferably oblong, but may be of any desired shape. In assembling the parts of the flexible buckle the inner loop 3 is first placed on the belt by inserting it 80 in the split end portion of the belt which is stitched transversely at 7^a to prevent further splitting or severing of the material of the belt and which tends to hold the loop in operative position. The inner side or bar of 85 the inner loop is confined between the inner and outsides formed by splitting the belt and the outer bar of the inner loop projects beyond the outer face of the belt and forms an 90 opening to receive the perforated end portion of the said belt. After the assembly of the inner loop the belt is stitched transversely, as indicated at 8, and the tongue 5 and pivot 6 are assembled, a suitable aperture 9 being provided in the front side of the split portion for the inner end of the tongue which may be provided with an eye 10 to receive the pivot but which may be formed 95 integral with the tongue, as illustrated in 100

Figs. 5 and 6 of the drawing and hereinafter more fully explained.

After the assembly of the tongue the split portion of the belt is stitched transversely on 5 both sides of the pivot as at 17, and longitudinally adjacent the edges of the belt as at 18. The belt is also stitched transversely as at 8^a and the outer loop 4 is then assembled by inserting its inner bar between the sides of the 10 split portion, after which the latter is stitched transversely adjacent the buckle end of the belt, as indicated at 11. Any desired manner of stitching may, of course, be employed and any other suitable means may be utilized for 15 connecting or securing together the inner and outer sides of the split portion of the belt. The tongue cooperates with the outer loop in the same manner as tongues of buckles of the same type cooperate with an outer bar. 20 The end portion of the belt constitutes the body portion of the buckle and provides a flexible buckle which will not only afford increased comfort by conforming to the configuration of the fitting flat against the body 25 of the wearer, but which will also afford flexibility of manipulation and enable the belt to be buckled and unbuckled more easily than belts having buckles of the same type in which the spaced bars or loops are rigidly connected 30 by integral metallic portions or equivalent structures.

In Figs. 5 and 6 of the drawing is illustrated another form of attaching the elements of the flexible buckle to the end of the 35 belt. Instead of splitting the end of the belt longitudinally a separate piece or patch 12 is stitched as shown at 19 around its marginal edges to the inner face or back of the belt adjacent the edges thereof to form with the 40 end portion of the belt inner and outer portions between which the inner and outer loops 12^a and 13, and the tongue 14 with its pivot 15 are secured by stitching in the manner heretofore explained.

45 The tongue 14 is provided with an integral pivot 15 and extends through an aperture 16 in the buckle end of the belt. The tongue cooperates with the outer loop in the manner heretofore explained. The separate piece or 50 patch 12 is preferably employed in the manufacture of belts of expensive leathers or materials in which it is preferable not to split the end of the belt longitudinally for one reason or another. The belt and the patch form 55 the inner and outer portions and provide the flexible connecting body portion of the buckle and the belt has the same flexibility of buckle structure as that illustrated in Figs. 1 to 4, inclusive.

60 What is claimed is:

1. A flexible buckle belt, comprising a belt having a buckle end and an end provided with holes, inner and outer loops secured to the buckle end of the belt and spaced apart and 65 projecting outwardly from the outer face of

the belt to form openings for the insertion of the other end of the belt over the outer face of the buckle end of the belt, and a tongue having a pivot secured to the belt between the inner and outer loops, said tongue cooperating with the outer loop and adapted to engage the end of the belt having the said holes, the belt between the inner and outer loops constituting the body or the connecting portion of the buckle to form a flexible buckle. 75

2. A flexible buckle belt, comprising a belt having a buckle end and an end provided with holes, inner and outer oblong loops spaced apart and extending transversely of the belt and having their inner sides secured to the 80 same, the said loops projecting outwardly from the outer face of the belt to form openings for insertion of the other end of the belt, and a tongue having a pivot secured to the belt at a point between the inner and outer loops, said tongue cooperating with the holes in the end of the belt and also with the outer loop and the portion of the belt between the loops constituting the body or connecting portion of the buckle to form a flexible buckle. 90

3. A flexible buckle belt, comprising a belt having a buckle end provided with inner and outer portions, inner and outer oblong buckle loops having their inner sides secured between the inner and outer portions of the belt, the 95 outer sides of the loops projecting from the outer face of the belt, and a tongue having a pivot secured between the inner and outer portions of the belt and cooperating with the outer buckle loop, the portion of the belt between the inner and outer loops constituting a flexible body portion for the buckle. 100

4. A flexible buckle belt, comprising a belt having a buckle end provided with inner and outer portions, the outer portion being provided with an aperture, inner and outer buckle loops having inner bars secured to the inner and outer portions of the belt at opposite sides of the said aperture, and a tongue 105 extending through the said aperture and having a pivot secured between the inner and outer sides of the belt, said tongue cooperating with the outer buckle loop and the portion of the belt between the loops constituting a flexible buckle body. 110

5. A flexible buckle belt, comprising a belt having a buckle end split longitudinally to provide inner and outer portions, the outer portion being provided with an aperture, inner and outer oblong loops secured between 120 the inner and outer portions of the belt and spaced apart and projecting outwardly from the outer face of the belt to form openings for the insertion of the other end of the belt, and a tongue extending through the said aperture and having a pivot secured between the inner and outer portions of the belt, said tongue cooperating with the outer buckle loop and the portion of the belt between the loops constituting a flexible buckle body portion. 125

130

6. A flexible buckle belt, comprising a loop adjacent the extremity of one end of the belt and projecting outwardly from the face thereof, and means engageable with the loop and the other end of the belt, said means being positioned on the belt inwardly of the loop and the said other end of the belt.
7. A flexible buckle belt, comprising spaced loops projecting outwardly from the face of the belt at one end thereof, one of said loops being adjacent the extremity of the said end of the belt, and means for engaging the other end of the belt, said means being positioned on the belt intermediate of the said loops.
- 15 8. A flexible buckle belt, comprising spaced loops projecting outwardly from the face of the belt at one end thereof, one of said loops being adjacent the extremity of the said end of the belt, and means for engaging the other

end of the belt, said means being positioned on the belt intermediate of the said loops, and being engageable with the loop at the extremity of the said end of the belt.

9. A flexible buckle belt comprising a belt having a buckle end provided at its inner face with a longitudinal patch forming inner and outer portions, inner and outer loops disposed transversely of the belt and secured between the inner and outer portions of the belt, a tongue having a pivot secured between the inner and outer portions of the belt between the inner and outer loops, said tongue cooperating with the outer loop, and the belt between the inner and outer loops constituting a flexible buckle body portion.

In testimony whereof I have hereunto set my hand.

EDWIN S. MIX.
